Joseph T. Yaksick(57) **CLAIM**

The ornamental design for an attachable cover for footwear, as shown and described.

DESCRIPTION

FIG. 1 is an isometric view of an attachable cover for footwear, showing my new design;

FIG. 2 is an enlarged front view thereof;

FIG. 3 is an enlarged rear view thereof;

FIG. 4 is an enlarged right side view with a left side view being the mirror image thereof;

FIG. 5 is a top view thereof; and,

FIG. 6 is a bottom view thereof.

The broken lines are for illustrative purposes only and form no part of the claimed design.
